UNITED STATES PATENT OFFICE.

CHARLES G. SCHMIDT AND JOHN A. F. HEINE, OF CINCINNATI, OHIO,
ASSIGNORS TO CINCINNATI BUTCHERS SUPPLY COMPANY, OF CIN-
CINNATI, OHIO.

REFRIGERATOR.

SPECIFICATION forming part of Letters Patent No. 726,995, dated May 5, 1903.

Application filed August 18, 1902. Serial No. 119,996. (No model.)

To all whom it may concern:

Be it known that we, CHARLES G. SCHMIDT and JOHN A. F. HEINE, citizens of the United States, residing in the city of Cincinnati, in the county of Hamilton and State of Ohio, have invented certain new and useful Improvements in Refrigerators; and we do declare the following to be a clear, full, and exact description thereof, attention being called to the accompanying drawings, with the reference-numerals marked thereon, which form also a part of this specification.

This invention relates to improvements in refrigerators of the kind illustrated in Patent No. 650,914, issued to Charles G. Schmidt, one of these present applicants. In said refrigerator the interior—that is, inner side—of the walls inclosing the food and provision compartments is lined with sheets of glass rigidly connected to an outer wooden frame in the manner stated in said patent. The objection to that construction was that in cases where this outer woodwork was not thoroughly seasoned and commenced to move by swelling, shrinking, or warping the glass could not follow, and broke as a result. Again, by reason of the intimate and rigid connection between these materials (glass and wood) any jar, knock, or concussion received on the outer side—as, for instance, during transportation or moving—would immediately be transmitted to the glass within, with results equally destructive.

To overcome these defects is the leading object of this invention, and the construction whereby it is attained is the leading feature thereof. In addition there are other features of construction, which will be referred to at the proper time.

In the following specification, and particularly pointed out in the claims following, is found a full description of the invention; together with its parts and construction, which latter is also illustrated in the accompanying drawings, in which—

Figure 1 shows in perspective view a refrigerator provided with the features of our invention. Fig. 2 is a vertical section of the same. Fig. 3 is a horizontal section of it. Fig. 4 is a perspective view of one of the panel-frames. Fig. 5 is an enlarged sectional

detail view showing construction at one of the corners. Fig. 6 shows in a perspective view the parts illustrated in Fig. 5. Fig. 7 is a fractional perspective view of one of the corners of the door, showing construction of the same.

In the drawings, 10 indicates such parts as sills, uprights, corner-posts, and cross-pieces of a skeleton frame. 11 is the outer wall of the refrigerator, attached to the outside of this skeleton frame. The inner wall 12 as far as it surrounds the provision-chamber 13, as well as floor and top thereof, consists of sheets of glass, as described in the former patent mentioned. They are of a size to merely cover the intended surfaces and do not lap at their corners or edges. Between these two parts 11 and 12 of the walls and as far as they form sides and bottom of the provision-chamber 13 there are independent panel-frames 14, (see Fig. 4,) which are fitted between the uprights, cross-pieces, and other parts of skeleton frame 10. They are provided with cross-pieces 15, flush with their inner side, so as to permit the sheets of glass 12, with interposed sheets of paper 16, to be placed evenly against them. The open space between these parts of the panel-frames and between wooden walls 11 and the sheets of paper 16 is filled in with non-conducting material 17, preferably mineral wool. These panel-frames, forming thus a backing for the sheets of glass, are held in place between the parts of skeleton frame 10 in a manner merely sufficient to retain their position, but not so rigid as to prevent them or frame 10 from partaking of such motions as are due to warping, shrinking, and swelling. For such purpose these frames are not fitted closely, and their connection is, as shown in the detail view in Fig. 5, by means of a limited number of screws 18, which pass through enlarged openings 19 in frame 14 and take into the contiguous parts of skeleton frame 10. The object of the sheets of paper is to confine the filling material 17 and also to serve as a cushion for the glass between it and the hard surface of the wood. These sheets of glass are simply set against the panel-frames 14, but are in no way connected thereto. They are held in position in the rear upright corners by

strips 20, which may be metal or wood and metal-plated, and which strips are secured by screws 21, passing diagonally through between the sheets of glass and into the corner-posts 5 of skeleton frame 10. To obtain sufficient space to permit passage of these screws and also to prevent the edges of the sheets of glass from touching each other and to fill out the angular space formed by and between 10 these edges, there is an additional filling or spacing strip 22, of rectangular profile, which is fitted into this angle and also held in place by the same screw 21. This latter also serves to hold in place a horizontally-projecting 15 bracket 23 by passing through an attaching-lug projecting from the inner corner of the same and which bracket, in conjunction with other brackets and projecting screw-hooks 24 in front, serves to support a shelf 25, of open 20 wirework, used to support some of the contents of the provision-chamber. At its rear edge this shelf is turned up, as shown at 26, to form a guard to protect the glass of the rear wall against articles shoved against it. 25 Around the bottom the construction is the same, a similar spacing-strip 22 being used upon which the upright sheets of glass rest, while the bottom sheet is laid in between these strips. At the front upright edges or 30 corners the glass sheets are held by angle-strips 27, which may be held in place by the screw-hooks 24, which serve at the same time to support the front corners of shelf 25, as already mentioned. At the top similar angle- 35 strips 28 are used, those at the edges of the circulation-openings 29 and 31 being used reversed, as shown at 32. The inner side of the doors 33 is also lined with glass, as shown at 34. These sheets of glass are set into a recess in the inner side of the doors and held 40 therein by cleats 35 taking over their edges and passing into the woodwork of the doors to a depth beyond the thickness of the glass. The cleats are secured by nails 36, driven 45 into the edge of the door and at such places as to catch these cleats. These latter, as well as the joints between the glass and wood, are covered and closed by an ornamental frame 37, preferably of bright metal. To 50 prevent any moisture deposited on the glass from creeping into the woodwork, particularly at the corners of the provision-chamber, the sheets of glass before being placed in position are provided with a coating of white 55 lead around their outer edges, as shown at 38.

Above the provision-chamber there is the ice-chamber 39, arranged in the usual manner with doors 41 in front or at the side, or at both places. It is lined out with zinc, the 60 lining of the bottom extending through circulation-openings 29 and 31 and somewhat below the lower edges of these openings to form drip-noses 42, which prevent moisture and condensation from reaching the top and 65 sides of the provision-chamber. Above, around the upper edges of these openings, this

lining is turned up to form ridges 43 to prevent the water from the melting ice from flooding the provision-chamber, which water is carried off through a drain-pipe 44, discharging at 45 into a suitable vessel or tank resting on the floor below the refrigerator. This space is closed in front by a swinging apron 46, behind which this tank is concealed. The ice rests on corrugated cross-pieces 47, supported on longitudinal rails 48 and forming the parts of the ice-rack, all of sheet metal. Rails 48 are perforated to permit the air which circulates through openings 29 and 31 to freely reach all parts and 75 spaces of the interior. To prevent any drippings from the ice passing through these openings, we provide hoods 49, supported between rails 48 and above these openings. Only one is needed in this case—that is, over 80 opening 29—since there is no ice above opening 31, such space being kept clear for circulating purposes, the ice being prevented from encroaching by a stop 51. Hoods 49 are hollow and inclose an air-space to prevent formation 85 of condensation on their under side.

It will be noted that by reason of the sheets of glass being loosely held in the manner shown the movements of the various parts of the woodwork, due to swelling, shrinking, 95 and warping, may proceed without interference with the glass and jars and concussions received from the outside are not transmitted.

Having described our invention, we claim 100 as new—

1. A refrigerator having the inclosing sides of its provision-chamber formed of sheets of glass, panel-frames against which they are placed, a skeleton frame within which these 105 panel-frames are contained, means connecting to the skeleton frame whereby the glass sheets are loosely held in position and an outer wall attached to the skeleton frame.

2. A refrigerator, the construction of which 110 comprises an open skeleton frame, an outer wall connected to the outside thereof, panel-frames loosely fitted into the open part thereof, screws whereby they are held in position within the skeleton frame, the openings for 115 them in the panel-frame being enlarged beyond the diameter of the holding-screws, sheets of glass forming the inclosing walls of the provision-chamber and means to hold them in position against the panel-frame 120 without rigid connection thereto.

3. A refrigerator, the construction of which 125 comprises in combination an open skeleton frame, an outer wall connected to the outside thereof, panel-frames loosely fitted into the open parts of this skeleton frame, sheets of glass forming the inclosing walls of the provision-chamber, placed against these panel-frames, but without connection thereto, angular strips in the corners of this provision-chamber covering the edges of contiguous 130 sheets of glass and screws passing through

the space between these latter and into the parts of the skeleton frame to hold these angular strips in position.

4. A refrigerator, the construction of which comprises in combination an open skeleton frame, an outer wall connected to the outside thereof, panel-frames loosely fitted into the open parts thereof, screws whereby they are held in position within the skeleton frame, the openings for them in the panel-frame being enlarged beyond the diameter of the holding-screws, sheets of glass forming the inclosing walls of the provision-chamber placed against these panel-frames but without connection thereto, angular strips in the corners of this provision-chamber covering the edges of contiguous sheets of glass and screws passing through the space between these latter and into the parts of the skeleton frame to hold these angular strips in position.
5. In a refrigerator having the inclosing sides and doors of its provision-chamber lined with sheets of glass, recesses in the inner side of the doors to receive these sheets, cleats taking over the edges of these sheets and attached to the woodwork of the door to hold these sheets in position and an ornamental frame to cover these cleats and the crevices between glass and woodwork.
6. A refrigerator having a provision-chamber and an ice-chamber above the same, a

horizontal partition between the two, openings in this partition to provide for circulation of air, an ice-rack in the ice-chamber upon which the ice rests, the same consisting of cross members and longitudinal members below them and a hood between these latter and above the openings in the horizontal partition mentioned, said hood being hollow so as to form an inclosed air-space.

7. In a refrigerator, the combination of a skeleton frame, an outer wall attached to the outer side thereof, sheets of glass on the inside forming the inclosing sides of the provision-chamber, angular strips in the corners of this provision-chamber at the edges of the sheets of glass and where they meet at corners, screws to hold these angular corner-strips in place, horizontally-projecting brackets 23 having attaching-lugs projecting from their inner corners and so interposed that the heads of the screws mentioned pass also through these lugs, thereby holding at the same time brackets 23 in position and a shelf supported on these latter.

In testimony whereof we hereunto set our signatures in the presence of two witnesses.
